P. NATHANSON ET AL

COP ATTACHMENT FOR LOOM SHUTTLES

Filed June 30, 1923

Inventors:

Philip Nathanson, Jacob Sonntag

By their Attorney, Lee. H. Math

UNITED STATES PATENT OFFICE.

PHILIP NATHANSON AND JACOB SONTAG, OF ALLENTEOWN, PENNSYLVANIA.

COP ATTACHMENT FOR LOOM SHUTTLES.

Application filed June 30, 1923. Serial No. 648,780.

To all whom it may concern:

Be it known that we, PHILIP NATHANSON and JACOB SONTAG, citizens of the United States, and residents of Allentown, county 5 of Lehigh, and State of Pennsylvania, have invented a certain new and useful Cop Attachment for Loom Shuttles, of which the following is a specification sufficient to enable those skilled in the art to which the 10 invention appertains to utilize the same.

Our improvement relates to means for mounting cops, so called, on the spindles of, and in, shuttles used in looms, and particularly looms used in the weaving of silk in 15 a manner well known in the art,—said cops being substitutes for the standard quills or wooden bobbins primarily intended for use in shuttles of this type of apparatus,—and the invention consisting essentially of a 20 basic coupling sleeve adapted to fit on the shuttle spindle and engage with the retaining shoulders on the latter, and also adapted to fit tightly within the rear portion of the hollow cop, whereby the latter functions 25 as the equivalent of the standard shuttle quill or spool, all as hereinafter fully set forth.

In the accompanying drawings we exemplify a practical embodiment of the essential 30 features of our invention, although we do not limit ourselves to the identical form and construction of parts shown, since modifications in minor details, and equivalent mechanical expedients, may be resorted to 35 with like result, and without departing from the spirit and intent of our invention in this respect.

With this understanding,

Fig. 1, is a face view of a shuttle of the 40 silk-loom type, without the quill or bobbin usually employed in connection therewith;

Fig. 2, is an elevation of a quill spool or bobbin such as designed primarily for use in the shuttle shown in Fig. 1.

Fig. 3, is a side elevation, and

Fig. 4, is a central longitudinal section of a cop bobbin;

Fig. 5, is a front end elevation of our cop bobbin coupling sleeve, upon an enlarged 50 scale;

Fig. 6, is a side elevation thereof; and

Fig. 7, a central longitudinal section thereof, on the same scale as that of Fig. 5;

Fig. 8, is an elevation of a cop bobbin and 55 wind as received for use in the shuttle;

Fig. 9, is a view of a cop bobbin mounted on one of our coupling sleeves and positioned in the shuttle, the silk wind of the bobbin being omitted;

Fig. 10, is a sectional elevation upon an 60 enlarged scale, illustrating the conjunctive combination of a cop bobbin with one of our coupling sleeves.

As is well known in the art of silk weaving, the shuttles S, are adapted primarily 65 to accommodate the standard wooden quill bobbin q, indicated in Fig. 2, of the drawing, being formed with a pivotally mounted and longitudinally split spindle s, adapted to fit tightly within the tubular 70 central portion of said quill bobbin q, the base of which is formed with an annular shoulder q', which fits in between the opposed jaws s', s', of the shuttle S, in such manner that the bobbin q, is held firmly 75 against longitudinal movement or play upon said spindle s.

The cop bobbins k, are also well known in the art, being used as substitutes for the 80 standard wooden quill bobbins q, upon occasion. They are made of paper or equivalent light weight material, and are relatively cheap as compared with the wooden quill bobbins q, which cost approximately 85 four and one-half cents a piece, whereas the cop bobbins k, cost only approximately forty-five cents a pound and average over two hundred cops to the pound, so that they are cheap enough to be discarded after first use,—it being understood that the 90 quill bobbins q, are of substantial structure and capable of repeated use to an indefinite extent.

Furthermore, the cop bobbins, on account 95 of their light weight, cost much less for transportation between mills, etc., than the heavier quill bobbins q, which are rewound upon occasion, so that cost of return transportation has frequently to be taken into account as well as the danger of breakage 100 or loss in transit, whereas the unwound cop bobbins are, under ordinary conditions of use, not alone worth the cost of transportation.

Heretofore, where cop bobbins k, have 105 been used in quill bobbin shuttles, such as shown in Figs. 1 and 9, of the drawings, a wedge has been inserted in the longitudinal split s', of the spindle s, to expand the said spindle s, to fit tightly within the cop bob- 110

bin tube, which is usually of truncated conoidal form. Or, in lieu of thus adapting the quill bobbin spindle s , as a mount for a cop bobbin k , the said spindle s , may be 5 placed in the shuttle S , by a cop spindle of special construction, but this involves considerable time and labor, and shortens the life of the shuttle, as the frequent removal and replacement of the trunnion pins 10 enlarges the pin holes, so that the pins are liable to fall out during the use of the shuttle, thus not only rendering the shuttle worthless, but otherwise resulting in serious loss and damage. Another disadvantage of 15 changing to a special cop spindle is that such spindles cannot be used for any other form of bobbin.

We obviate these difficulties by our coupling sleeve C , consisting of a tubular stem c , the forward portion of which is slotted 20 to form expansible tongues c' , and the rear of which is formed with a basic annular shoulder c^2 , adapted to fit between the spring jaws s', s' , of the shuttle S , as shown 25 in Fig. 9, of the drawings.

In use, the tubular stem c , of our coupling sleeve C , is inserted in the rear end of a cop bobbin k , as shown more particularly in Fig. 10, of the drawings, and the coupling sleeve C , and cop bobbin k , then together positioned on the spindle s , of the shuttle, the elastic resilient slotted portion s^2 , of said spindle, expanding the sleeve tongues c' , so that the latter bear forcefully 35 against the adjacent inner surface of the cop bobbin, creating sufficient frictional resistance to hold both bobbin k , and coupling C , together practically as a unitary structure for all practical purposes, and so that 40 the spring jaws s' , contacting with the basic annular shoulder c^2 , of the coupling sleeve C , hold the cop bobbin k , securely against longitudinal movement as effectually as the

wooden quill bobbin q , is held under ordinary conditions of use.

Our cop bobbin coupling sleeve C , is simple and inexpensive, and can be manipulated with facility, being readily attached to or disconnected from the cop bobbin, and easily placed upon or removed from the spindle, and by its use said cop bobbin is rendered as effectual as the standard quill bobbin. Furthermore, its use does not impair the shuttle in any particular, said shuttle and its spindle remaining intact, and 55 equally adapted to the use and requirements of both quill and cop bobbins.

What we claim as our invention and desire to secure by Letters Patent is,

1. In combination with a shuttle provided with a hinged bobbin spindle of the character designated, a coupling sleeve for hollow cop bobbins adapted to fit within one end of a cop bobbin and over the shuttle spindle, said coupling sleeve being formed with an 60 expansible portion for contactual engagement with the interior surface of a cop bobbin, substantially in the manner and for the purpose set forth.

2. In combination with a shuttle provided 70 with a hinged bobbin spindle of the character designated, a coupling sleeve for hollow cop bobbins adapted to fit within one end of a cop bobbin and over the shuttle spindle, said coupling sleeve being formed with an 75 expansible forward portion for contactual engagement with the interior surface of a cop bobbin, and with a shouldered base for engagement with the bobbin-retaining jaws, substantially in the manner and for the purpose described.

PHILIP NATHANSON.
JACOB SONTAG.
